UNITED STATES PATENT OFFICE

170,595

COMBINATION HAIR CURLER AND COMB

Arnold L. Lewis, Los Angeles, Calif.

Application May 4, 1953, Serial No. 24,825

Term of patent 14 years

(Cl. D86—8)

To all whom it may concern:

Be it known that I, Arnold L. Lewis, a citizen of the United States, residing at Los Angeles, in the county of Los Angeles, State of California, have invented a new, original, and ornamental Design for a Combination Hair Curler and Comb, of which the following is a specification, reference being had to the accompanying drawing forming part thereof, in which:

Fig. 1 is a perspective view of a combination hair curler and comb, showing my new design;

Fig. 2 is a side elevational view thereof;

Fig. 3 is a top plan view thereof;

Fig. 4 is a bottom plan view thereof;

Fig. 5 is an end elevational view as seen from the left of Fig. 2; and

Fig. 6 is an end elevational view as seen from the right of Fig. 2.

I claim:

The ornamental design for a combination hair curler and comb, as shown.

ARNOLD L. LEWIS.
